(57) **CLAIM**

I claim the ornamental design for a dispenser for safety razor blade assembly, as shown and described.

DESCRIPTION

FIG. 1 is an upper perspective view of a dispenser for safety razor blade assembly.

FIG. 2 is a lower perspective view thereof.

FIG. 3 is a top view thereof.

FIG. 4 is a bottom view thereof.

FIG. 5 is an end view thereof.

FIG. 6 is an end view, opposite the view of FIG. 5.

FIG. 7 is a side view thereof.

FIG. 8 is an opposite side view thereof.

FIG. 9 is an upper perspective view of the dispenser in an open position; and,

FIG. 10 is a top orthogonal view of the dispenser in an open position.

1 Claim, 4 Drawing Sheets

FIG. 3

FIG. 4

FIG. 5

FIG. 6

FIG. 7

FIG. 8
